CLAIM

The ornamental design for a medical device for debridement of tissue, as shown and described.

DESCRIPTION

FIG. 1 is a right side elevational view of the medical device for debridement of tissue showing my new design;

FIG. 2 is a left side elevational view thereof;

FIG. 3 is a rear elevational view thereof;

FIG. 4 is a front elevational view thereof;

FIG. 5 is a top view thereof;

FIG. 6 is a bottom view thereof; and,

FIG. 7 is a perspective illustration showing a front view and a right side view thereof.

1 Claim, 4 Drawing Sheets
